DOOR SECURING MECHANISM

William Young, Washington, D. C.

Application July 12, 1937, Serial No. 153,221

13 Claims. (Cl. 292—25)

This invention relates to mechanism for securing doors, hatches and other closures in closed position.

A principal object of the invention is to provide a door securing mechanism which may be quickly operated with a minimum of effort to lock or unlock the door and which is of such construction as to be instinctively operated in the correct manner to produce the result desired, even under extremely adverse conditions, such as in the presence of smoke or in the absence of light.

The invention also has for its object the provision of a door securing mechanism which, under ordinary operative conditions, is incapable of being forced into releasing position by pressures to which the door may be subjected.

A primary feature of the invention consists in providing a closure with a rotatable shaft extending along the inner face thereof, the shaft being adapted to operate a plurality of members each having a shouldered portion adapted to have hooked engagement with brackets or the like for securing the closure in closed position.

Another feature of the invention consists in providing a closure with rotatable shafts extending lengthwise adjacent opposite side edges thereof, each of said shafts being provided with a plurality of members movable in planes substantially normal to the axis of rotation of the shaft and said members respectively having shouldered portions adapted to have hooked engagement with brackets or the like for securing the closure against opening movement, means being mounted on the closure between the shafts for rotat- 35 ing the latter.

A further feature of the invention consists in providing the closure with a plurality of angularly disposed shafts respectively extending lengthwise adjacent adjoining side edges thereof, said shafts having shouldered members adapted to have hooked engagement with means for securing the closure against opening movement and being movably connected whereby they are adapted to rotate simultaneously to actuate the shouldered 45 members.

A still further feature of the invention consists in providing a door or the like with a rotatable shaft which extends along the inner face thereof and has a plurality of shouldered members adapted to have hooked engagement with brackets for securing the door against opening movement, the brackets being adjustable so as to compensate for wear of the parts and inaccuracies of manufacture and thus insure the maintenance 55 of a tight closure of the door at all times.

Other and more specific features of the invention, residing in advantageous forms, combinations and relations of parts, will hereinafter appear and be pointed out in the claims.

In the drawings, wherein the invention is shown as applied to a bulkhead door, 5

Figure 1 is an elevational view of the inner face of the door and adjacent portions of a bulkhead.

Figure 2 is a detail sectional view taken on line 2—2 of Figure 1. 10

Figure 3 is a detail sectional view taken on line 3—3 of Figure 1.

Figure 4 is a fragmentary sectional view taken on line 4—4 of Figure 3.

Figure 5 is an enlarged fragmentary view illustrating the relative position of parts of the mechanism as the closure approaches closed position. 15

Figure 6 is an enlarged fragmentary view showing the relative position of parts of the mechanism when the closure is fully closed. 20

Figure 7 is an enlarged view of a portion of the means whereby the mechanism is operated.

Figures 8, 9, and 10 are diagrammatic views showing successive positions occupied by a portion of the operating means as it moves from 25 door securing to door releasing position.

Figure 11 is a rear view of one of the adjustable brackets.

Figure 12 is a view similar to Figure 6 illustrating a door having a slightly different construction 30 adjacent its edges.

Figure 13 is a similar view illustrating still another door construction.

Although, for purposes of illustration, the invention has been shown as applied to a bulkhead 35 door, it will be appreciated that it is capable of general application and may be used with equal facility in any environment where it is desired to effect the tight closure of an opening.

Referring more particularly to the drawings, 40 1 indicates a metal door which is hingedly mounted upon a bulkhead 2 for closing an opening in the latter. The particular door illustrated is reinforced by a centrally located inwardly offset portion 3 and by a plurality of transverse plate 45 members 4, which extend continuously across the inner face of the door and terminate at the inturned marginal flanges 5 thereof. The hinge mounting of the door is of conventional construction including hinge straps 6 secured to the door 50 and provided with elongated slots for receiving pins or the like 7 carried by hinge butts 8 mounted upon the bulkhead.

The mechanism for securing or locking the door in closed position includes two rotatable shafts 55

9 which extend lengthwise along the inner face of the door adjacent opposite side edges thereof, being mounted in suitable bearings 10 which are secured in any desirable manner to the door.

5 Each of shafts 9 is preferably formed in a plurality of tubular sections and the adjacent ends of the sections of each shaft are so connected that the sections are capable of slight angular movement with respect to each other to compensate for misalignment of the bearings. The connections between the shaft sections may be advantageously effected by forming one of the adjoining ends of each section with an enlarged portion 11 into which the adjoining end of the adjacent section projects and by providing the latter section with laterally extending bosses 12 which are received within slots or recesses 13 in the enlargements 11.

Rigidly mounted on each of the shafts 9 is a plurality of members 14, each of which has a shoulder or ledge 15 adapted to hook over the outer end of a bracket 16 which is mounted on the inner side of the bulkhead adjacent the opening therein.

25 While the brackets may be of any suitable shape and construction, they may be advantageously provided with a base plate 17 for attachment to the bulkhead and with an outwardly projecting portion 18, the outer end of which is formed with an inclined face 19 for cooperating with the ledge or shoulder of the associated hook. These cooperating surfaces of the hooks and brackets are so disposed with respect to the axis of rotation of the hooks when the door is closed and locked that the 35 hooks cannot be forced out of engagement with the brackets by pressure transmitted to the door, even though the pressure be the maximum the door itself is designed to withstand.

Extending through the door and journaled 40 within a cylindrical portion 20 of a casting 21 mounted upon the inner face of the door is a rotatable shaft 22 forming part of mechanism for inducing rotation of the shafts 9. Intermediate its ends, shaft 22 may be integrally formed with a collar 23 which is confined between the outer end of the cylindrical portion 20 and the flanged end of a screw threaded member 24 to prevent longitudinal movement of the shaft. Rigidly mounted on the inner end of shaft 22 is a plate-like member 25 having two oppositely arranged curved slots 26 which are eccentric with respect to the axis of the shaft. Extending within the slots are bosses or pins 27 respectively formed on links or bars 28, each of which is pivotally connected at its outer end to an arm or the like 29 rigid with the adjacent shaft 9. At their inner ends, each of the links is bifurcated, as indicated at 30, so as to straddle shaft 22 and be supported thereby.

60 As the slots 26 in plate member 25 are eccentric with respect to the axis of rotation of shaft 22, it will be perceived that, when the shaft is rotated, the links are caused to move toward or away from each other, depending upon the direction in which 65 the shaft is rotated, and thus through the intermediary of arms 29 impart rotation to shafts 9 and hook members 14. The sides of the slots 26 adjacent the ends thereof occupied by pins 27 when the hooks are in locking engagement with 70 their brackets are practically straight and approximately normal to a line passing through the pins and the axis of shaft 22. By this arrangement, inward movement of the links to impart an unlocking rotation to the hooks cannot be accomplished except by rotating plate member 25. Fur-

thermore such formation of the slots also enables a powerful leverage to be obtained in the final closing operation of the door.

To enable shaft 22 to be easily rotated from either side of the door, both ends of the shaft are rigidly provided with levers, the lever on the outside of the door being designated by the reference numeral 31 and the lever on the inside of the door being indicated by the reference numeral 32 and being preferably formed as an integral extension 10 of plate member 25. Both levers are so arranged that, when the door is secured in closed position, they project in a substantially horizontal direction beyond the edge of the door remote from the hinged edge thereof, and that, when the securing 15 members are released, they extend upwardly in substantially vertical positions with their inner ends terminating inwardly of the upper edge of the door.

In order that one closing the door from the outside may know when it has been closed sufficiently to enable the hooks 14 to engage brackets 16, a keeper 33 is mounted on the bulkhead adjacent the opening for cooperating with lever 31. The keeper has an upwardly extending part 34 terminating in an outwardly flared portion 35 to provide an inclined surface which is cooperable with lever 31 as it moves downwardly for forcing the door into a position wherein the hooks will properly engage the brackets. The upper end of 30 the keeper is so disposed that for the lever 31 to cooperate with it in the intended manner, the hooks cannot be rotated sufficiently as to assume 35 positions preventing or interfering with the closing of the door.

To secure the closure along its top and bottom edges, as well as along its side edges, additional locking members 36 are employed. Each of these locking members is of the same design as the hook members 14 and they are each mounted upon a 40 stub shaft 37 supported in bearings 38 of the same construction as bearings 10. Each of shafts 37 is provided with a sector gear 39 which is adapted to mesh with a similar gear 40 mounted on the adjacent end of the adjoining shaft 9. In this manner, it will be perceived that the stub shafts 37 and their hook members 36 will be rotated by and simultaneously with shafts 9.

When links 28 are actuated to rotate shafts 9 and 31, their outer ends move in arcuate paths 50 and, unless the inner ends thereof are caused to move in corresponding paths, the links will be subjected to bending strains and, in addition, pins 27 will angle slightly and thus tend to bind within slots 26. To cause both ends of each link to move 55 in similar paths and thereby maintain the links in substantial parallelism at all times, the rear face of the inner portion of one of the links is provided with a projection 41 for cooperating with a rib or the like 42 on the outer end of the screw 60 threaded cap 24 and the inner face of plate 25 is provided with spaced brackets 43 and 44 for successively cooperating with opposite edges of the inner portion of the other link. Projection 41 has a convexly curved outer surface of the same 65 curvature as the arc through which the outer ends of the links move and brackets 43 and 44, which may be conveniently of angle shape, have concavely curved outer edges also of the same curvature.

The respective positions occupied by projection 41 and by brackets 43 and 44 when the door is locked are shown in Figures 7 and 8. When plate 25 is rotated to move the links inwardly to unlock the door, bracket 43 begins to move out of engage- 75

ment with the adjacent link but at the same time projection 41 moves into engagement with rib 42 and thus causes the inner ends of the links to move toward plate 25 in an arcuate path similar to that traversed by the outer ends of the links. At the time the highest point on projection 41 comes into engagement with rib 42, bracket 43 is moving out of engagement with the lower edge of the cooperating link and bracket 44 is moving into engagement with the upper edge thereof, as shown in Figure 9. Continued rotation of plate 25 thus brings bracket 44 into play to guide the inner ends of the links in the desired arcuate path during the remaining distance through which the links travel inwardly. The positions occupied by the brackets with respect to their cooperating link after the mechanism has been moved as far as possible in an unlocking direction are illustrated in Figure 10. In moving the mechanism from unlocked to locked position, the inner ends of the links are caused to move in the desired arcuate path by being successively actuated by the right hand half of projection 41, as viewed in Figure 7, and by bracket 43.

To provide a seal against the passage of smoke, gas and the like, as well as to make the door water-tight, the inner face of the door is provided with a gasket 45 which extends inwardly from the marginal flange 5. The gasket may be of any suitable material and is mounted between a rigid plate-like member 46 and an angle member 47. While the space between members 46 and 47 may be such as to receive a gasket of the desired thickness, it is preferred to make it sufficiently large to accommodate filler plates 48 having one or more elongated openings for receiving the inner end of screws 49 which are threaded in the angle iron 47. By employing filler plates of varying thickness, it will be perceived that gaskets of varying thickness may be likewise employed. Although screws 49 may be employed to clamp the gasket in place by bearing against the filler plates instead of extending through openings therein, this has been found unnecessary provided the gasket is inserted within the space between members 46 and 47 while under slight compression.

The inner portion of plate member 46 is offset rearwardly from the gasket, as at 50, and it projects beyond the inner edge of the latter to afford a seat against which the outer end of a marginal flange 51 surrounding the opening in the bulkhead is adapted to abut, when the door is fully closed. Rigid with flange 51 and having a portion spaced laterally therefrom is a member 52 which is adapted to engage the gasket 45 prior to the time the outer edge of flange 51 abuts against the offset portion 50 of plate 46. Thus as the door approaches closed position, member 52 deflects the gasket rearwardly against the offset portion 50 and firmly compresses it when the door is fully closed.

Upon being fully closed, flanges 51 and member 52, together constituting laterally spaced portions, are respectively in engagement with offset portion 50 of plate 46 and gasket 45 and the latter is firmly compressed. The gasket, of course, makes the door tight against water and other fluids and the metal to metal contact of portion 50 and flange 51 effectively prevents fire from passing through the opening. It is to be particularly noted that this contact between portion 50 and flange 51 prevents fire on the inside of the door from reaching the gasket and thus, under such condition, the seal afforded by the gasket will be preserved.

Instead of having the offset portion of plate member 46 project sufficiently beyond the inner end of the gasket to afford an abutment for the inner end of flange 51, it may only project sufficiently so as to be disposed closely contiguous to the outer face of the end portion of flange 51, as indicated at 53 in Figure 12. With this arrangement substantially all the advantages of a metal to metal contact between the door and the bulkhead are maintained, but closing movement of the door is not arrested by a rigid abutment and, for this reason, the gasket may be compressed any amount permitted by the door securing mechanism.

It will, of course, be appreciated that various sealing arrangements may be used on doors provided with the securing mechanism forming the subject-matter of the present invention. An illustration of another form of door to which the invention is applicable is shown in Figure 13. The door there shown is provided with a molded sealing strip 54 which is adapted to be engaged substantially midway between its side edges by the outer end of a flange 55 bounding the opening in the bulkhead.

In cases where the sealing gasket is under considerable pressure, it oftentimes happens, particularly with doors having gaskets of the type illustrated in Figure 13, that the gasket becomes permanently grooved and, therefore, loses its sealing effect. Moreover, it sometimes happens that on account of wear of door parts and the securing mechanism, as well as on account of other causes, such as inaccuracies of manufacture causing misalignment of the parts, the securing mechanism will not secure all portions of the door in a fully closed position. To eliminate these difficulties and thus insure the door being maintained tightly closed at all times, the brackets 16 with which the hooks cooperate are adjustably mounted instead of being fixedly mounted. To this end, the base plates 17 of each of the brackets is provided with a plurality of elongated slots 56 for receiving pins 57, which are preferably made rigid with the bulkhead, and have their outer ends screw threaded to receive nuts 58 adapted to bear against the outer face of the base plate. In order that the brackets may be rigidly secured in a desired position of adjustment, the under side of each is serrated, as indicated at 59, so as to cooperate with the serrated outer face of a plate 60 which is interposed between the bracket and the bulkhead and is immovable with respect to the latter. It will thus be seen that, should the portion of the door adjacent the hook illustrated in either Figure 6 or Figure 13 not be properly closed when the hook has been rotated in a locking direction as far as possible, all that would be necessary to effect the tight closure of that portion of the door would be to shift the cooperating bracket slightly to the right.

In the operation of the mechanism to secure the door in closed position, the door is first caused to assume a position such that lever 31 may be moved downwardly behind keeper 33. As the lever moves down the inclined portion of the upper end of the keeper, the door is forced into closed position and shafts 9 and 37 are rotated through the intermedacy of plate 25 and links 28 to cause the hooks 14 and 36 to move into cooperative engagement with their respective brackets. When the outer ends of the hooks first engage the brackets, the door will occupy a position with respect to the opening similar to that shown in Figure 5, wherein it will be ob-

served member 52 has engaged the gasket and deflected it rearwardly a slight amount. Thus with the door only partially closed, a sealing effect is obtained against the passage of smoke, gas and the like. With the hooks in the position indicated in Figure 5, further downward movement of either of the levers 31 and 32 will result in the door being forced to tightly closed position by the hooks camming over the outer ends 10 of the brackets, the ultimate position assumed by the hooks being indicated in Figure 6.

It will be manifest to those skilled in the art that various modifications and rearrangements of parts of the specific structure illustrated and described herein may be made without departing from the spirit and scope of the invention as defined in the appended claims.

This application is a continuation in part of my copending application Serial No. 123,500, filed 20 February 1, 1937.

What I claim is:

1. Mechanism for securing a door, hatch or other closure in closed position, said mechanism including a shaft rotatably mounted upon the 25 door and extending lengthwise along a face thereof, a plurality of members movable by said shaft in planes substantially normal to the axis of the shaft, each of said members having a shouldered portion adapted to have hooked engagement with means mounted adjacent the opening to be closed by the door, and means for 30 rotating said shaft to actuate said members.

2. Mechanism for securing a door, hatch or other closure in closed position, said mechanism 35 including a shaft rotatably mounted upon the inner face of the door and disposed adjacent to and substantially parallel with a side edge thereof, a plurality of members mounted upon and movable by said shaft in planes substantially 40 normal to the axis of the latter, each of said members having a shouldered portion adapted to have hooked engagement with means mounted adjacent the opening to be closed by the door, and means revolvably mounted on the door for 45 rotating said shaft to actuate said members.

3. Mechanism for securing a door, hatch or other closure in closed position, said mechanism including two shafts rotatably mounted upon the door and respectively extending lengthwise along 50 the inner face of the door adjacent opposite side edges thereof, each of said shafts being provided with a plurality of members movable in planes substantially normal to the axis of the shaft, said members respectively having shouldered portions 55 adapted to have hooked engagement with means mounted adjacent the opening to be closed by the door, and means mounted on the door between said shafts for rotating the latter to actuate said members.

60 4. Mechanism for securing a door, hatch or other closure in closed position, said mechanism including a shaft rotatably mounted upon the door and extending lengthwise along a face thereof, a plurality of bearings for said shaft, said shaft comprising a plurality of sections capable 65 of slight angular movement with respect to each other to compensate for misalignment of the bearings, a plurality of members mounted on said shaft and movable thereby in planes substantially normal to the axis of the shaft, each of said members having a shouldered portion adapted to have hooked engagement with means mounted adjacent the opening to be closed by the door, and means for rotating said shaft to 70 actuate said members.

5. Mechanism for securing a door, hatch or other closure in closed position, said mechanism including a shaft rotatably mounted upon the door and extending lengthwise along a face thereof, a plurality of members movable by said shaft and respectively having shouldered portions adapted to have hooked engagement with means mounted adjacent the opening to be closed by the door, and means carried by the closure for rotating said shaft to actuate said members, said means including rotatably mounted means whose axis of rotation is substantially normal to the door, an arm rigid with the shaft, and link means connected to said arm and movable by said rotatable means. 15

6. Mechanism for securing a door, hatch or other closure in closed position, said mechanism including a shaft rotatably mounted upon the door and extending lengthwise along a face thereof, shouldered members mounted upon said shaft 20 adapted to have hooked engagement with means mounted adjacent the opening to be closed by the door, and means carried by the door for rotating said shaft to actuate said members, said means including rotatable means having a curved 25 portion eccentric with respect to the axis of rotation thereof, an arm rigid with said shaft, and link means connected to said arm and having a portion cooperable with said curved portion whereby upon movement of said rotatable means 30 said link means is moved to rotate said shaft.

7. Mechanism for securing a door, hatch or other closure in closed position, said mechanism including two shafts rotatably mounted upon the door and respectively disposed adjacent to and 35 substantially parallel with opposite side edges thereof, each of said shafts being provided with a plurality of shouldered members respectively adapted to have hooked engagement with means mounted adjacent the opening to be closed by the 40 door, and means carried by the door for rotating said shafts to actuate said members, said means including rotatable means mounted between said shafts and having a plurality of curved portions eccentric with respect to the axis 45 of rotation of said means, arms respectively rigid with said shafts, and link means connected to said arms and respectively cooperable with said eccentric portions whereby movement of said rotatable means induces rotation of said shafts. 50

8. Mechanism for securing a door, hatch or other closure in closed position, said mechanism including a plurality of angularly disposed shafts rotatably mounted upon the door and respectively extending lengthwise along a face of the door adjacent adjoining side edges thereof, each of said shafts being provided with one or more shouldered members adapted to have hooked engagement with means mounted adjacent the opening to be closed by the door, means mounted upon the door and operatively connected to one of said shafts for imparting rotation thereto, and means movably connecting said shafts for causing them to rotate simultaneously. 55

9. Mechanism for securing a door, hatch or other closure in closed position, said mechanism including shafts rotatably mounted upon the door and respectively extending lengthwise along its inner face adjacent side edges thereof, said shafts having means engageable with portions 65 mounted adjacent the opening to be closed by the door for securing the door in closed position, and means for rotating said shaft, said means including movable means mounted upon the closure, arms respectively rigid with said shafts, 70

links overlapping the inner face of the closure pivotally connected to said arms and cooperable with said movable means for imparting movement of the latter to said shafts, and means for maintaining said links in substantial parallelism during movement thereof by said movable means.

5 10. Mechanism for securing a door, hatch or other closure in closed position, said mechanism including shafts rotatably mounted upon the door and respectively extending along a face of the door adjacent side edges thereof, members rigid with the shafts and movable thereby for engaging means to secure the door in closed position, means for rotating said shafts including links 15 having their outer ends respectively pivotally connected to the shafts and movable in arcuate paths, and means cooperable with said links for causing the inner ends thereof to move in corresponding arcuate paths.

20 11. Mechanism for securing a door, hatch or other closure in closed position, said mechanism including shafts rotatably mounted on the door and respectively extending lengthwise along a face of the door adjacent side edges thereof, a plurality of members mounted upon and movable by the shafts adapted to engage means to secure the door in closed position, each of said shafts having a rigid arm, links movably mounted on the door, the outer ends of the links being respectively pivotally connected to said arms and being movable in arcuate paths, rotatable means for moving said links to actuate said shafts, and a plurality of means for successively coacting with the respective links to cause the inner ends 35 thereof to move in arcuate paths similar to the outer ends.

25 12. Mechanism for securing a door, hatch or other closure in closed position and for tightly maintaining the door against abutment means surrounding the opening to be closed by the door, said mechanism including a shaft rotatably mounted on the door and extending lengthwise along a face of the door substantially parallel with and adjacent to an edge thereof, members movable by the shaft in planes substantially 40 normal to the plane of the door, brackets mounted adjacent an edge of the opening to be closed by the door for respectively cooperating with said

members, each of said brackets having an outer surface disposed at an acute angle to the plane of the door opening and each of said members having a shouldered portion provided with a surface adapted to have extended bearing on said 5 surface of the adjacent bracket for securing the door in closed position, and means enabling said brackets to be adjustably movable toward and away from the adjacent edge of said opening in a direction substantially parallel with the 10 plane of the opening whereby the door, in different positions of adjustment of the brackets, will be tightly closed against the abutment means and the extended bearing engagement of the co-acting surfaces of the brackets and members in 15 different positions of adjustment of the door will be maintained.

13. Mechanism for securing a hinged door in tightly closed position and for tightly maintaining the door against abutment means surrounding the opening to be closed by the door, said mechanism including a shaft rotatably mounted upon the door and extending lengthwise along a face of the door adjacent the edge thereof opposite the hinged edge, members mounted upon 20 said shaft and movable in planes substantially normal to the axis thereof, brackets mounted adjacent an edge of the opening to be closed by the door for respectively cooperating with said members, each of said brackets having an outer 25 surface inclined with respect to the plane of the door opening and each of said members having a shouldered portion provided with a surface adapted to have extended bearing on the inclined surface of the adjacent bracket to secure 30 the door in closed position, and means enabling said brackets to be adjustably movable toward and away from the adjacent edge of the door opening in a direction substantially parallel with the plane of the opening whereby the door, in 35 different positions of adjustment of the brackets, will be tightly closed against the abutment means, and the extended bearing engagement of the coacting surfaces of the brackets and members in the different positions of adjustment of 40 the door will be maintained.

45 WILLIAM YOUNG.
